UNITED STATES PATENT OFFICE.

FRANCIS L. COOK, OF SPRINGFIELD, MASSACHUSETTS, ASSIGNOR OF ONE-HALF TO FRANCKE W. DICKINSON, OF SAME PLACE.

SPINNING-TOP.

SPECIFICATION forming part of Letters Patent No. 673,831, dated May 7, 1901.

Application filed July 25, 1900. Serial No. 24,758. (No model.)

To all whom it may concern:

Be it known that I, FRANCIS L. COOK, a citizen of the United States of America, and a resident of Springfield, in the county of Hampden and State of Massachusetts, have invented certain new and useful Improvements in Spinning-Tops, of which the following is a full, clear, and exact description.

This invention relates to improvements in spinning-tops, the objects being to produce a top to be spun by the use of a cord, but by a different manipulation from that employed for spinning ordinary tops; to produce a top capable of being spun which is of a peculiar and novel form; to produce improved sounding devices in the top, and to provide, in combination with the top proper, having an attenuated or an elongated stem-like body adapted to be wound by the spinning-cord, a socketed holder or handle in which the top may be held preparatory to spinning and from which the top may be thrown when spun or upon which holder the top may be supported while spinning by the exercise of a skilful action to be acquired.

The invention consists in the constructions and combinations of parts, all substantially as hereinafter fully described, and set forth in the claims.

30 The improved top is illustrated in the accompanying drawings, in which—

Figure 1 is a central vertical section through the top and the socketed holder therefor, the spindle-like body of the top being within the socket of the holder and shown as wound in readiness to be whirled or spun and also thrown out from the socket in the holder. Fig. 2 is a plan view of the top. Fig. 3 is a horizontal sectional view taken on line 3 3, 40 Fig. 1.

Similar characters of reference indicate corresponding parts in all of the views.

In the drawings, *a* represents the top, and *b* the holder.

45 The top is of a mushroom shape, having a flattened circular head or one that is decidedly spheroidal, as seen at *c*, and a comparatively thin tapered shank or stem *d*, which constitutes the top-body.

50 The holder *b* is constructed with a deep axial upwardly-open socket *f*, of a size to freely

and loosely receive therein the stem-like body of the top when wound with the spinning-cord *g*.

As shown in Fig. 1, when the wound stem 55 of the top is set down into the socket *f* in the holder the top receives its support entirely by the under side of the head, which rests on the upper end of the holder, leaving the stem and surrounding cord free and loose 60 within the inner wall of the holder, so that when the cord is drawn to spin the top there is practically no impediment or friction imparted by contact of any part of the wound top with the wall of the socketed holder. 65

Although the top may be turned from a single piece of wood or integrally constructed from any other suitable material, for the purposes of practicability and economy I prefer to employ a two-part construction, as shown 70 in Fig. 1, wherein the flat, circular, or spheroidal head *c* has the circular central socket *h*, while the top-body *d* has the upper cylindrical extension *i* above the shoulder *j*, said cylindrical portion entering with a close fit 75 into the said socket, the bottom of the top-head coming to a rest against said shoulder *j*, and the parts are here preferably united by gluing.

I have shown the device constructed as a 80 sounding-top, the top-head having a transverse passage *h* intersecting the opening *m*³, which is formed leading downwardly centrally from the upper side of the top-head. The said opening is formed step-like or of 85 varying diameters, whereby at the base of its larger portion *m* is produced the rest *m*² for the metallic semispheroidal centrally-apertured shell *n* and whereby is produced at *o* the rest for the reed *q*, it being noticed that 90 the upper end of the extension *i* terminates slightly below the top of the socket *h* in the top-head, whereby the upper end of the said part *i* is rendered the base of a depression in which said reed is fitted. The lower portion 95 of the said opening *m* is from the upper end of the socket *h* upwardly flaring, the surface thereof being substantially a reversed counterpart of the said shell *n*, so that the whistle-cavity at *p* is constituted.

I do not lay claim to a spinning-top having transverse or radial passage or passages com-

municating with a vertical passage in which a whistle is applied, but claim herein the construction shown, whereby the lower flaring surface of the cavity m forms the rest for the 5 semispheroidal centrally-apertured shell n , which latter part, together with the part forming the rest therefor and thereunder, makes the whistle-chamber.

The tapered spindle-like body of the top is 10 wound with the cord, as indicated in Fig. 1, and the wound body is entered within the socketed holder b , with the extremity of the cord extending beyond the top of the holder laterally, as shown.

15 While grasping the holder b in one hand and giving the quick draft on the cord the top will not only have imparted thereto a whirling motion for the spinning thereof, but it will also be given a rising motion or jump, 20 so that it may after rising out of the holder fall to and spin upon the floor or other support therefor.

Within the mouth of the socket f in the holder is formed the annular ledge t , which 25 may have a flat surface, as indicated by the full lines, or it may be channeled or trough-like, as indicated by the dotted lines t' in Fig. 1. Now when the cord is drawn to spin the top and to give it the rising motion the operator, by manipulation which he may acquire by practice, can have the peg or point 30 of the top stem or body caught on the said ledge t , as indicated by the dotted lines in Fig. 1, to spin upon the said ledge of the holder, which latter is held by the hand.

35 The head of the top provided with the opening and passages shown and with the whistle device and the reed will when spun, because of the draft of air produced through the 40 transverse passage, cause the simultaneous sounding of both the whistle and the reed.

Having thus described my invention, what I claim, and desire to secure by Letters Patent, is—

1. A spinning-top having a head and a central spindle-like depending stem combined with the holder b having an axial socket therein deeper than the stem of the top and of a size to loosely receive therein the whole length of the stem and the spinning-cord wound 45 thereon, while the head of the top rests on the upper end of the holder, substantially as described and shown.

2. The combination with the holder b having the upwardly-opening socket f provided 50 with an internal annular edge t below its mouth, of the top comprising a spindle body d and a widened head c , substantially as described.

3. The top consisting of the head c having 60 central opening m at upper side with flaring base portion m^2 and downwardly-opening socket h , the spindle-like body d having an annular flange j and cylindrical upper end extension i fitted and secured in said socket h , 65 with its upper end slightly below the upper end of said socket the metallic circular centrally-apertured device n having downwardly-deflected edges resting on said base portion m^2 the reed resting on the upper end of said 70 extension i , and said head c and connected extension i being provided with a transverse passage k with which a reduced downward continuation of the opening m communicates, substantially as described and shown. 75

Signed by me at Springfield, Massachusetts, in presence of two subscribing witnesses.

FRANCIS L. COOK.
